(57) **CLAIM**

The ornamental design for a paving element, as shown and described.

DESCRIPTION

FIG. 1 is a perspective view of a first variant of the design. FIG. 2 is a perspective view of another variant of the design. FIG. 3 is a perspective view of another variant of the design. FIG. 4 is a perspective view of another variant of the design. FIG. 5 is a perspective view of another variant of the design. FIG. 6 is a perspective view of another variant of the design. FIG. 7 is a perspective view of another variant of the design. FIG. 8 is a perspective view of another variant of the design. FIG. 9 is a perspective view of another variant of the design. FIG. 10 is a perspective view of another variant of the design.

FIG. 11 is a perspective view of another variant of the design.

FIG. 12 is a perspective view of another variant of the design.

FIG. 13 is a perspective view of another variant of the design.

FIG. 14 is a perspective view of another variant of the design; and,

FIG. 15 is a perspective view of another variant of the design.
